WINDER

Burt A. Peterson, Rockford, Ill., assignor to Barber-Colman Company, Rockford, Ill., a corporation of Illinois

Application February 6, 1937, Serial No. 124,380

22 Claims. (Cl. 242—35.6)

The invention pertains to winders of the general type shown in Patent No. 1,267,977, dated May 28, 1918, in which a series of yarn masses or "cheeses" are wound to a desired diameter under the control of a winder-tending mechanism or "traveler." More particularly, the invention aims to provide an improved mechanism for automatically determining the quantity of yarn wound on the cheeses.

10 Winders as heretofore constructed have embodied full-cheese measuring devices of a character such that without manual adjustment the machine is incapable of producing cheeses of more than one size. An important object of the 15 present invention is to provide for the automatic production of cheeses containing different measured quantities of yarn.

A further object is to provide a measuring means operative automatically in the travel of the winder-tending mechanism to produce two or 20 more different sizes of cheeses.

Still another object is to produce a winder in which the traveling mechanism is equipped with a cheese measuring means operative at spaced points in the travel of the mechanism under the control of two or more adjusters to produce two or more sets or groups of cheeses with the cheeses of one group of a different predetermined diameter than the cheeses of the other group or 25 groups.

The objects of the invention thus generally stated, together with other and ancillary advantages are attained by the construction and arrangement shown by way of illustration in the accompanying drawings and constituting a 30 preferred embodiment of my invention.

In the drawings:

Figure 1 is a fragmentary front elevational view of a winder embodying my invention.

Fig. 2 is a diagrammatic view of the winder frame and illustrating the location of the adjusters for the cheese measuring device.

Fig. 3 is a fragmentary sectional view taken approximately in the plane of line 3 of Fig. 1, and illustrating the means operative under the control of the cheese measuring device to limit the size of the cheeses by interrupting the winding of yarn thereon.

Fig. 4 is a fragmentary view in perspective illustrating the full cheese measuring device and one of the adjusters therefor.

The winder-tending mechanism comprises generally a framework or carriage 7 arranged to travel upon the main frame 8 of the winder for successive association with a series of winding

units. For this purpose the latter is equipped with a rack 9 with which meshes a gear 10 suitably driven from the traveling mechanism, the construction and arrangement being substantially as disclosed in said Patent No. 1,267,977.

The means for measuring the cheeses is mounted on the traveling mechanism and comprises, as best shown in Fig. 4, a feeler shoe 11 mounted on the rear end of an arm 12 and arranged for operative association with cheeses of which one only is shown at 13. Each of the cheeses is mounted on an arm 13a, in a manner well known in the art so as to be capable of swinging from a normal operative or winding position in driving contact with a rotating drum (not shown) upwardly and thence outwardly into a "thrown-out" position (Fig. 4) for engagement by the feeler shoe 11 on the traveling mechanism.

The arm 12 is pivotally mounted on a shaft 14 and is adapted to be lowered and raised periodically to carry the shoe 11 toward and from the cheese 13. Such periodic motion of the arm 12 is derived from a cam 15 constantly driven in the operation of the traveling mechanism and having a roller follower 16. The latter is mounted on the rear end of an arm 17 fulcrumed at its forward end on a shaft 18. The rear end of said arm 17 is connected by a link 19 with the arm 12 at a point adjacent its fulcrum on the shaft 14. 12a is a spring tending to swing the arm 12 toward the cheese under the control of the cam 15.

The cam 15 is mounted on a constantly driven vertical shaft 20 and makes one complete revolution in the movement of the traveling mechanism from one winding unit to the next. As clearly shown in Fig. 4, the cam has a depression 21 therein and the arrangement is such that in its approach to a cheese to be measured, the arm 12 is held raised to position the under-surface of the shoe 11 in a horizontal plane above the uppermost surfaces of the cheeses 13. Then as, in the travel of the mechanism, the shoe is positioned above the cheese, the depression 21 in the cam permits the descent of the shoe toward or into feeling relation to the cheese.

The position assumed by the arm 12 under the control of the shoe 11 when a cheese reaches a desired predetermined diameter, is utilized to discontinue the winding of additional thread on the cheese. To this end, the arm 12 has rigid therewith a depending arm 23 carrying at its lower end a gauge plate 24 having in its lower forward corner a notch 25; and associated with this gauge plate is a control rod 26 operative when the gauge

plate and rod occupy a predetermined relation to initiate the operation of means for preventing the reserve thread from entering the knitter mechanism, thereby interrupting the operation 5 of winding additional thread from the reserve bobbin into the cheese.

As shown in Fig. 4, the control rod 26 is disposed at right angles to the surface of the plate 24, so that the latter forms an abutment for engagement by the right hand end of the rod when disposed rearwardly of the notch 25 in the plate. Adjacent the plate 24, the rod 26 is slidably supported in a guide plate 27. At its other end it is pivotally connected to a short arm 28 which 15 for a reason presently to appear may be termed the latch arm. This arm has a pin 29 to which is connected a spring 30 acting to move the feeler rod 26 toward the gauge plate and through the notch 25 when permitted to do so by the position 20 of the plate.

The means for interrupting the winding operation in response to a movement of the rod 26 through the notch 25 of the gauge plate 24, is arranged for actuation in the rotation of the 25 shaft 20. This means comprises a throw-out finger 31 shown at the lower left of Fig. 4. As in prior machines, this finger is operative to engage and move out of the path of the knot-tying device (not shown), the reserve thread leading 30 from the bobbin. Herein, said finger 31 is pivotally mounted on a shaft 32 and has rigid therewith a slotted arm 33 for receiving a pin 34 on the end of an actuating arm 35. The latter is connected by a yoke 36 with a vertically 35 spaced arm 37, both arms being mounted to turn on a vertical shaft 38. The finger 31 is held in its normal position by a spring 38a tending to maintain a stop screw 36a on the yoke 36, in contact with a stationary part of the traveler frame. In Fig. 3, the finger 31 is shown out of 40 its normal position indicated by dotted lines.

Also pivotally mounted on the shaft 38 is a bifurcated actuating member 39 carrying double roller followers 40 and 41 respectively engaging 45 with cams 42 and 43 fast on the shaft 20. These cams and rollers constitute a double roller cam mechanism of a well known character operating to impart a positive oscillating motion to the member 39, the arrangement being such that 50 the member 39 is oscillated once for each revolution of the shaft 20.

When the control rod 26 is permitted to move through the notch 25 of the gauge plate by reason of the attainment of the cheese to a predetermined size, a connection is effected as an incident to such movement of the rod, between the actuating member 39 and the arm 37 connected with the throw-out finger 31. For this purpose, the latch arm 28 is pivotally mounted 60 on the forward end of the arm 37 and carries rigid therewith a latch dog 44. Also the bifurcated actuating member 39 has rigid with one arm 45 thereof, a latch block 46 having an inclined surface underlying the dog 44 and formed 65 with a groove 47 adapted to receive the dog as an incident to the movement of the control rod by the spring 30. Normally the dog rests on the inclined surface of the block at the right hand side of the groove 47 so that the control rod 26 is held in its withdrawn position. In each revolution 70 of the cam shaft the latch block is actuated in timed relation to the feeling movement of the shoe 11, but until the cheese has attained its predetermined size the gauge plate 24 is swung 75 forwardly (Fig. 4) into a position such as to

block the control rod 26 and thus prevent the dog 44 from entering the groove 47. When, however, the downward movement of the feeler arm 12 is interrupted by a full cheese of a predetermined size, the notch 25 in the gauge plate is 5 positioned to receive the control rod 26 and release the same to movement by the spring 30, thereby causing the dog 44 to enter the groove 47. Thereafter the actuating member 39 is moved to the left in Fig. 4 to swing the arm 35 against 10 the action of the spring 38a and thus move throw-out finger 31 rearwardly (Fig. 3) and at the same time to retract the control rod 26 for reengagement with the gauge plate 24 which by this time has been moved forwardly by the cam 15. 15

The sensitive point of control governing the motion of the control rod 26 relative to the gauge plate 24 may, it will be seen, be varied by changing the relation of the rod to the plate, or more specifically by shifting the position of the rod 20 relative to the notch 25 in the plate. According to my invention, this construction and arrangement is utilized in the automatic production of two or more groups of yarn masses of different sizes, and this is attained in the present instance 25 by a size determining or setting means comprising a plurality of adjusters generally designated 48 (Figs. 2 and 4), and a cooperating shifting device 48a mounted on the traveling mechanism and operatively connected with the guide plate 30 27 for the control rod 26 so as to determine the position of the latter relative to the gauge plate.

As best shown in Fig. 4, said guide plate 27 is carried by the lower end of an arm 49 pivotally mounted on the shaft 14 and rigidly connected 35 by a yoke 50 with an upstanding arm 51 which in turn is connected by a link 52 with a shift lever 53. The latter is mounted to turn on a vertical pivot pin 54 and carries at its free end a roller 55 mounted upon the winder-tending 40 mechanism and movable in its travel into operative association with the adjusters 48. 40

The adjusters 48 comprise in the present instance, two plates 56 and 57 fast upon a block 58 suitably mounted for lateral adjustment relative to the path of the roller 55 by means of a bracket 59 secured to the winder frame 8 (Fig. 1). The plates are spaced apart a distance conforming to the diameter of the roller and are formed with opposing cam faces 56' and 57' diverging 50 so as to receive and guide the roller into a predetermined position. 50

It will be observed that the two plates 56 and 57 are at all times fixed relative to each other but are bodily adjustable transversely of the 55 path of movement of the roller 55 in the travel of the winder-tending mechanism. The two plates form between them a guideway for receiving the roller 55 and operate through the lever 53, link 52 and arms 51 and 49 to determine the position of the guide plate 27 and its control rod 26 relative to the gauge plate 24 as the latter reaches the end of its forward movement (Fig. 4) in the operation of the cam 15 and the feeler shoe 11. As the winder-tending 60 mechanism approaches a given winding unit the guide plate 27 and rod 26 are positioned according to a desired predetermined size of the yarn mass to be produced at this unit. If the yarn mass has attained less than said predetermined size, the feeler shoe 11 will upon its descent as permitted by the cam 15, cause the gauge plate 24 to assume a position with the notch 25 forwardly of the rod 26. The rod is thus blocked against movement and the winding operation 65 70

permitted to continue. On the other hand if the cheese has attained its predetermined size the gauge plate 24 will be limited in its forward movement so as to permit the passage of the rod 26 through the notch 25. When this occurs, the dog 44 will be permitted to enter the groove 47 to effect a connection between the arm 37 and its actuating member 39 resulting in the interruption of the winding operation through the actuation of the throw-off finger 31.

Referring now to Figs. 2 and 4, it will be apparent that in the travel of the tending mechanism, the position of the guide plate 27 and therefore of the control rod 26 relative to the gauge plate 24 will be determined by the adjuster plates 56 and 57 and that by changing the relative positions of the adjusters 48 transversely of the path of travel of the roller 55 (Fig. 2) the control rod 26 will be automatically shifted at predetermined points by the adjusters 48 and thereby vary the sensitive control point which determines the size of the cheeses through the interruption of the winding operation. After movement into association with a given adjuster, the setting effected thereby is maintained for succeeding winding units until readjustment occurs by engagement of the roller 55 with another differently set adjuster. Thus for each setting of the plate 27, the cheeses are wound to a size determined by such setting.

To insure the maintenance of the guide plate 27 in a set position after the roller 55 has passed through and beyond a given adjuster 48, a suitable retaining device is provided (Fig. 1). As shown (Fig. 1) this device comprises a plunger 60 mounted in a depending arm 61 rigid with the frame 7 and pressed by a spring 62 into frictional engagement with the surface of the guide plate 27.

It will be observed that my invention provides for the automatic production in a single winder of cheeses of two or more different sizes and therefore containing different measured quantities of yarn. In practice, the several adjusters 48 are first set according to the different sizes to which the cheeses are to be wound, four adjusters being shown in Fig. 2, so that four groups of cheeses of different sizes may be produced. According to the setting of these adjusters, the guide plate 27 is positioned to govern the operation of the control rod 26 in response to the movement of the gauge plate 24 which in turn is responsive to the size of the yarn masses, for the purpose of interrupting the winding operation and thereby limiting the size of the yarn masses being wound. As the winder-tending mechanism moves from one winding unit to the next, the feeler shoe 11 is lowered by the operation of the cam 15 and moves the gauge plate 24 forwardly a distance depending upon the extent of downward movement of the shoe 11 as permitted by the size of the cheese when the cam follower 16 enters the depression 21 of the cam 15.

As the cheese approaches its predetermined maximum diameter, the extent of movement of the gauge plate 24 is limited by the engagement of the shoe with the cheese, and if the cheese has attained its predetermined maximum diameter, the control rod 26 is permitted to move under the influence of its spring 30 through the notch 25 of the gauge plate. When this occurs, the latch dog 44 enters the groove 47 in the latch plate 46, and in the ensuing oscillation of the bifurcated member 39, the arms 37 and 35 are operated to swing the throw-out finger 31

into the position shown in dotted lines in Fig. 3. In this position of the finger, the reserve thread is deflected so as to be prevented from entering the knot-tying mechanism and thereby discontinues the winding of yarn onto the yarn mass. 5 as explained in the aforesaid Patent No. 1,267,977.

I claim as my invention:

1. A winder comprising, in combination, a main frame, a traveling mechanism mounted for movement on said frame, a plurality of yarn 10 masses with which said traveling mechanism co-operates in succession, said traveling mechanism having means for interrupting the winding of yarn onto said masses, and means for governing the operation of said interrupting means including an adjusting device variably operative at spaced points in the travel of the mechanism to limit variably the sizes of said yarn masses. 15

2. A winder comprising, in combination, a series of yarn mass supports, a traveling mechanism movable relative to said supports and including feeler means sensitive to the sizes of the yarn masses being wound, said yarn masses being arranged in a plurality of groups, and means coacting with said feeler means and operative 20 automatically in the travel of said mechanism to limit variably the sizes of the yarn masses in the respective groups.

3. A winder comprising, in combination, a series of yarn mass supports, a traveling mechanism 30 movable relative to said supports and including feeler means sensitive to the size of the yarn masses being wound, and means coacting with said feeler means and operative automatically in the travel of said mechanism to limit 35 variably the sizes of the different yarn masses.

4. A winder comprising, in combination, a series of yarn mass supports, a traveling mechanism movable relative to said supports, said yarn 40 masses being arranged in a plurality of groups, a measuring device on said mechanism operative to interrupt the winding of yarn on said masses, and means operated in the travel of said mechanism for automatically adjusting said measuring device to vary the amount of yarn wound on the 45 masses of each group.

5. A winder comprising, in combination, a main frame, a traveling mechanism mounted for movement on said frame, means for supporting a plurality of yarn masses, and means operable 50 in the travel of said mechanism for interrupting the winding of yarn onto said masses, comprising a feeler movable into engagement with the yarn masses, a gauge element positioned by said feeler, a yarn deflecting member, means for actuating said member, a sensitive control element, a plurality of adjusters mounted on said frame and operatively associated with said control element to determine the position thereof relative to said gauge element, said control element being 55 movable relative to said gauge element in a predetermined relation of said elements, and means operative as an incident to such movement of the control element to govern the actuation of said deflecting member. 60

6. A winder having a frame, means for supporting a plurality of yarn masses, and a traveling mechanism mounted for movement on said frame and having a measuring device for determining the amount of yarn to be wound on said 70 masses, said measuring device including a gauge element responsive to the sizes of the yarn masses being wound, a control element movable relative to the gauge element in a predetermined relation of the elements, a positioning member operatively 75

- connected with said control element to move it, and a series of cam devices mounted on said frame and engageable by said positioning element in the travel of said mechanism.
- 5 7. A winder comprising, in combination, a main frame, a traveling mechanism mounted for movement on said frame, and means for supporting a plurality of yarn masses, said mechanism having means for measuring the amount of yarn to be wound on said masses including a feeler engageable with the yarn masses, a gauge element movable with said feeler, a control element movable relative to the gauge element in a predetermined relation of said elements, a movable support for the control element, an adjusting device mounted on said main frame, a positioning element mounted on the traveling mechanism and engageable with said adjusting device for movement thereby into a predetermined position, and means operatively connecting said positioning element with said movable support to shift the position of the control element relative to the gauge element.
- 10 8. A winder comprising, in combination, a main frame, a traveling mechanism mounted for movement on said frame and means for supporting a plurality of yarn masses, said mechanism having means for measuring the amount of yarn to be wound on said masses including a feeler engageable with the yarn masses, a gauge element movable with said feeler, a control element movable relative to the gauge element in a predetermined relation of said elements, a movable support for the control element, a cam device mounted on said main frame, a positioning element mounted on the traveling mechanism and engageable with said cam device for movement into a predetermined position, means operatively connecting said positioning element with said movable support to shift the position of the control element relative to the gauge element, said cam device providing a through-passage having opposed guiding surfaces for said positioning element, and means for supporting said device for bodily movement on said frame transversely of the path of said mechanism.
- 15 9. A winder comprising, in combination, a traveling mechanism having a feeler, power driven means, means controlled by said power driven means to move said feeler into engagement with a yarn mass, a gauge plate the position of which is determined by said feeler, a device for interrupting the winding of yarn onto said mass, a control rod, means operative automatically in the travel of said mechanism to shift said rod laterally into a predetermined position along the face of said gauge plate according to the size of the yarn mass to be wound, an actuating member operatively associated with said power driven means for periodic movement thereby, a second member connected with said device to move it, a latch device operative to establish a driving connection between said members and operatively connected with said control rod, and spring means for actuating said control rod and said latch device, said control rod being operable to actuate said latch device when the gauge plate occupies a predetermined position relative to the control element.
- 20 10. A winder comprising, in combination, a traveling mechanism, power driven means, a feeler, means controlled by said power driven means to move said feeler into engagement with a yarn mass, a gauge member the position of which is determined by said feeler, a device for

interrupting the winding of yarn onto said mass, a sensitive control member, means operative automatically in the travel of said mechanism to shift said control member relative to said gauge member according to the size of the yarn mass to be wound, and means operative when said members occupy a predetermined relation for establishing an operative connection between said power means and said device.

25 11. A winder having, in combination, a support for a yarn mass, traveling means including a feeler for engaging the yarn mass, a cam normally controlling the movement of said feeler, a device for interrupting the winding of yarn onto the mass, and means cooperating with said feeler to control said device including a sensitive control member positioned according to the size of the yarn mass to be wound, said means being operative as an incident to the movement of the feeler and control member into a predetermined relation, the position of said feeler being determined jointly by said cam and the size of the yarn mass.

30 12. A winder comprising, in combination, a traveling mechanism having a feeler for movement into engagement with a yarn mass, a gauge element movable in response to the movement of the feeler, a sensitive control element arranged for movement relative to the gauge element in a predetermined position of the gauge element, a power driven shaft, a cam on said shaft operative to effect the movement of said feeler into engagement with the yarn mass, a device for interrupting the winding of yarn on the mass, a member operatively connected with said device to move it, an actuating member, a second cam on said shaft for operating said actuating member, and means operable in the movement of said control element to establish an operative connection between said members.

35 13. A winder comprising, in combination, means for supporting a yarn mass, a traveling mechanism having a feeler for engaging said yarn mass, a gauge element responsive to the movements of said feeler, power driven means including cam means operative to impart periodic movement to said feeler, a sensitive control element adapted to coact with said gauge element and movable relative thereto in a predetermined position of the latter, a device for interrupting the winding of yarn onto said mass, an operating member for said device, a cam actuated member, means providing a disengageable connection between said members and acting in response to the movement of said control element to effect the operation of said device, and spring means for moving said control element, said power driven means being operative in the movement of said device to restore said control element against the action of said spring means.

40 14. A winder comprising, in combination, means for supporting a yarn mass, a traveling mechanism having a feeler for engaging said yarn mass, a gauge element responsive to the movements of said feeler, power driven means including cam means operative to impart periodic movement to said feeler, a sensitive control element adapted to coact with said gauge element and movable relative thereto in a predetermined position of the latter, a device for interrupting the winding of yarn onto said mass, an operating member for said device, a cam actuated member, means providing a disengageable connection between said members and acting in response to the movement of said control element to

- effect the operation of said device, and spring means for moving said control element, said power driven means being operative in the movement of said device to restore said control element against the action of said spring means, and said first cam means being operative upon the restoration of the control element to move said gauge element into blocking relation to the control element.
- 10 15. A winder comprising, in combination, means for supporting a yarn mass, a traveling mechanism having a feeler engageable with said yarn mass, a gauge element responsive to the movements of said feeler, a constantly driven vertical cam shaft, a cam on said shaft operative to impart periodic movements to said feeler, a sensitive control element adapted to coact with said gauge element and movable relative thereto in a predetermined position of the gauge element, a device for interrupting the winding of yarn onto said mass, an operating member for said device, an actuating member operatively associated with said shaft for periodic movement in the rotation of the shaft, and means providing a disengageable connection between said members and acting in response to the movement of said control element to effect the operation of said device.
16. A winder having, in combination, a support for a yarn mass, traveling means including a feeler for engaging the yarn mass, a device for interrupting the winding of yarn onto the mass, and means cooperating with said feeler to control said device including a sensitive control member positioned according to the size of the yarn mass to be wound, said means being operative as an incident to the movement of the feeler and control member into a predetermined relation.
- 40 17. A winder comprising, in combination, means for supporting a yarn mass, a gauge element adapted to occupy different positions according to the size of the yarn mass, a member to be operated, a sensitive control element movable relative to the gauge element in a predetermined relationship of said elements, said control element being shiftable to vary the point at which said predetermined relationship is established by movement of the gauge element, a power driven actuator, and means operative in the movement of the control element when the aforesaid relationship is established to connect said member to said actuator.
18. A winder comprising, in combination, a feeler engageable with a yarn mass, a gauge element movable by said feeler so as to occupy different positions according to variations in the size of the yarn mass, a member to be operated, a sensitive control element movable relative to the gauge element in a predetermined relationship of said elements, said control element being shiftable to vary the point at which said predetermined relationship is established by
- the movement of the gauge element, and means operative in the movement of the control element when the aforesaid relationship is established to govern the operation of said member.
19. A winder comprising, in combination, means for supporting a series of yarn masses, a traveling mechanism having feeler means responsive to the sizes of the yarn masses, a gauge element adapted to occupy various positions along a predetermined path according to variations in the sizes of the yarn masses, a member to be operated when any of the yarn masses attain a predetermined size as determined by said feeler means, means governing the operation of said member including a control element movable transversely of the aforesaid path of movement of the gauge element upon the establishment of a predetermined relationship between said elements, and means operative automatically in the travel of said mechanism to shift said control element in a direction parallel with said path of movement of the gauge element to vary the point at which said predetermined relationship is established.
20. A winder having a frame, means for supporting a series of yarn masses arranged in a plurality of groups, a mechanism arranged to travel on said frame and having a device operative to discontinue the winding of yarn onto said yarn masses, a detector responsive to the sizes of the yarn masses, a plurality of adjusters on said frame one for each of said groups, a member shiftable under the control of said adjusters in the travel of said mechanism, and power driven means operative under the joint control of said detector and said member to actuate said device.
21. A winder having a frame, means for supporting a series of yarn masses arranged in a plurality of groups, a mechanism arranged to travel on said frame and having a device operative to discontinue the winding of yarn onto said yarn masses, and means governing the operation of said device including a feeler responsive to the sizes of the yarn masses, a plurality of adjusters on said frame one for each of said groups, and means operating under the joint control of said feeler and the respective adjusters in the travel of said mechanism for initiating the operation of said device.
22. A winder having a frame, means for supporting a series of yarn masses, a mechanism arranged to travel on said frame and having a device operative to discontinue the winding of yarn onto said yarn masses, and means controlling the operation of said device including a detector on said mechanism responsive to the sizes of the yarn masses and means operable in the travel of said mechanism and cooperating with said detector to initiate the operation of said device.

BURT A. PETERSON.
